DESIGN FOR A KNITTED CAP OR SIMILAR ARTICLE

Samuel Kaplan, Hillside, N. J.

Application June 20, 1939, Serial No. 85,583

Term of patent 14 years

To all whom it may concern:

Be it known that Samuel Kaplan, citizen of the United States and resident of Hillside, in the county of Union and State of New Jersey, has invented a new, original, and ornamental Design for a Knitted Cap or Similar Article, of which the following is a specification, reference being had to the accompanying drawing forming part thereof, in which,

Fig. 1 is a perspective view showing the front and side of a knitted cap embodying my new design; and

Fig. 2 is a rear elevational view thereof.

The characterizing feature of my design resides in the knitted cap disclosed having ribs arranged as shown.

I claim:

The ornamental design for a knitted cap or similar article, substantially as shown and described.

SAMUEL KAPLAN.
